REVERSIBLE PLOWSHARE STRUCTURE

William I. Wheeler, Scottville, Ill.

Application June 7, 1949, Serial No. 97,598

1 Claim. (Cl. 97—125)

1

This invention relates generally to the class of plows and is directed particularly to improvements in plowshares.

A principal object of the present invention is to provide in an earth working plow, an improved share structure which is designed for reversal so that two blade edges may be provided upon the one share for the reversal and employment of a second blade when the first used blade has become dulled.

Another object of the invention is to provide an improved plowshare construction having a removable double edge blade, wherein the body of the share and the blade portion are joined together so as to provide a relatively smooth surface leading onto the surface of the moldboard to which the share is attached.

Another object of the invention is to provide in a plow construction a master share element which is detachably connected to the moldboard in the customary manner whereby removal of the share as a whole may be effected if and when desired, with a blade forming a part of the master share element and detachably connected therewith.

Still another object of the invention is to provide a construction of the above described character, wherein the said blade has each of its two long sides beveled to provide cutting edges, the master share element having a correspondingly beveled surface for matching the bevel of either side of the blade whereby to facilitate the connection of the blade onto the master element to form a complete share unit.

Still another object of the invention is to provide a plowshare blade having two working edges and oppositely directed points at the ends of the share, whereby the share may be reversed for putting the second edge into service after the first edge has become dulled or otherwise unfit for use.

Still another object of the invention is to provide a double edged double pointed reversible blade for a plowshare wherein a novel means is employed for locking the blade to the landside of the share, whereby a strong and rigid construction is obtained.

The invention will be best understood from a consideration of the following detailed description taken in connection with the accompanying drawings forming a part of the specification, with the understanding, however, that the invention is not to be limited to the exact details of construction shown and described since obvious

modifications will occur to a person skilled in the art.

In the drawings:

Figure 1 is a view of the moldboard side of an earth working plow showing in association therewith a landside and reversible blade constructed in accordance with an embodiment of the present invention.

Figure 2 is a view in perspective of the blade structure from the rear.

Figure 3 is a rear perspective view of a modified form of the double edge blade structure wherein the cutting edge of the blade at both sides extends straight to the plow point.

Figure 4 is a detail view in perspective of the rear side of one of the blades showing an interlocking connection between the point and the forward end of the landside of the plow.

Figure 5 is a sectional view taken substantially on the line 5—5 of Figure 1.

Figure 6 is a view in elevation of the moldboard side of a plow showing the double edge blade forming the complete share as distinguished from the construction shown in Figure 1 where the blade forms a part only of the share.

Figure 7 is a view in rear elevation of the double edge share shown in Figure 1 without the interlocking connection between the point of the share and the landside.

Figure 8 is a sectional view taken substantially on the line 8—8 of Figure 6.

Figure 9 is a sectional detail illustrating the manner in which the double edge blade may be applied directly to the bottom square cut edge of a moldboard designed to have the conventional share attached thereto.

Figure 10 is a detail view of master element of a slip share or quick detachable share having incorporated therewith the double edge blade of the present invention.

Figure 11 is a view in rear elevation of one end of a share showing an interlocking connection between the point and the adjacent part of the landside.

Figure 12 is a view of the landside of a plow showing the manner in which the landside is employed to support the point of a double edge blade or share of the character illustrated in Figures 6 and 7.

Referring now more particularly to the drawings Figure 1 illustrates a modified share construction wherein a double edge blade constructed in accordance with the present invention forms a part thereof. In this illustration the numeral 10 generally designates the usual or

conventional moldboard which has a straight or square cut bottom edge at 11 against which is fixed a correspondingly formed edge of a conventional share.

In accordance with one manner of carrying out the present invention such conventional share may be modified to have secured thereto the double edge share blade which is generally designated 12.

The modified conventional share is designated 13 and this has formed integral therewith at the landside of the plow, the landside bar 14 which, for the application of one style of blade, is cut at an oblique angle as indicated at 15.

The double edge share construction or the blade 12 therefor, comprises a long body of steel which is designated 16, the length of which is considerably greater than the length of the bottom edge 12 or of the modified share or master element 13. This blade bar 16 has the oppositely directed obliquely extending integral points 17 at the two ends thereof, the landside faces 18 of which are approximately parallel.

Each longitudinal edge of the blade bar 16 is beveled as indicated at 19 to provide a cutting edge 20. Each of these cutting edges extends forwardly along the shearing or cutting side of the point as indicated at 21.

Each of the points has a thickened landside portion 22 which extends rearwardly from the point through approximately half the length of the landside face 18 as shown in Figure 2 and such thickened portion terminates in the rearwardly directed abutment shoulder 23 against which the edge 15 of the landside bar bears.

As shown in Figure 5 the retained portion of the modified standard share structure 13 has the bottom edge thereof beveled as indicated at 24 to correspond with the bevel 19 at either side of the blade bar 16. When the blade bar is placed in position with one beveled edge 19 against the beveled edge 24 and the shoulder 23 against the angled end 15 of the landside bar, the forward face of the moldboard will present a smooth surface across which the turned soil moves in the use of the plow. Conventional securing means may be employed for coupling the blade bar 16 to the retained portion of the conventional share structure, as indicated at 26 and the customary means is employed for securing the share portion 13 to the bottom edge of the conventional moldboard, such means not being illustrated in the figures under consideration.

It will be readily seen upon reference to Figure 1 that when the double edge share or share blade is in position one point 17 will extend forwardly in the customary or conventional manner and the other point will be disposed a substantial distance rearwardly of the moldboard and will be extending upwardly from the edge of the blade which is in service. Since the points are of duplicate form it will be seen that when the point in service and the edge corresponding thereto becomes damaged, dulled or otherwise unfit for use the blade can be removed and reversed so as to bring a new point and cutting edge into service.

In Figure 3 is illustrated a double edge share blade constructed in accordance with the present invention which corresponds in width and in the formation of the ends to a conventional removable blade. This blade is generally designated 27 and has the two ends cut obliquely to form the landside faces 28. Each longitudinal

edge of this blade is beveled as at 29 to provide a cutting edge 30 and such edges, as shown, extend directly or in a straight line to the point 31 of the blade whereas in the form shown in Figures 1 and 2 such edge curves forwardly to follow the adjacent side of the elongated or forwardly extending point 17.

The points 31 are thickened toward the rear through approximately half the length of the face 28, as indicated at 32 whereby there is formed a rearwardly facing shoulder 33 against which the angled forward face of the landside bar bears.

In Figure 4 there is illustrated a blade which is generally designated 34. One end only of such blade is shown to illustrate a manner in which an interlocking connection may be established between the point 35 of the blade and the forward end of the landside bar which is designated 36. In this construction the thickened part 37 of the point has its rear side in the form of a V notch 38 and the forward end of the landside bar is correspondingly pointed as indicated at 39 to fit in such notch. This arrangement tends to prevent deformation of the point under strains to which the point may be subjected as the same is put into use.

In the form of the invention thus far described the share structure has been illustrated and described as comprising a master element which consists of a portion of the conventional share, and a double edged double pointed blade. Figure 6, however, illustrates the double edge, double pointed blade as constituting the complete share.

In the illustration of the above referred to form of the invention the moldboard is generally designated 40 and the bottom edge thereof is ground to a bevel as indicated at 41 in Figure 9 to correspond to the bevel 42 upon either of the longitudinal edges of the share which is generally designated 43. The share as illustrated constitutes a single plate or bar of steel in which the two longitudinal edges are beveled as shown to form the cutting edges 44 and each end is extended obliquely to provide the ground penetrating point 45.

In the double edge, double point structure illustrated in Figures 6, 7 and 9 the bar is of the same thickness throughout from point to point and is, accordingly, placed upon the lower edge of the moldboard and secured by suitable conventional securing elements here shown as straps 46 although it is to be understood that the invention is not restricted to this method of securing the share since it will be readily obvious that bolts, lugs, clips or other securing elements may be employed.

While in Figures 6 and 8 the lower edge of the moldboard has been shown as beveled to conform to the bevel 42 of the share it will be readily apparent upon reference to Figure 9 that the share may be applied directly to the square cut edge of the moldboard of conventional form or construction such as that shown in Figure 1. In such a case the lower edge 47 of the moldboard 48 would have one corner positioned against the beveled edge or beveled surface 42 of the share and the securing strap 49 would extend across the small gap between the adjacent edges of the two parts 48 and 43 as illustrated. This would, of course, form a slight overlap of the upper edge of the share and the front face of the moldboard and would not, of course, be as desirable an arrangement as that shown in Figures 5 and/or 8

although such an arrangement might be effected if necessary without detracting from the advantages of the invention.

Figure 10 illustrates a master element construction which is generally designated 50 in which the forward end of the landside bar 51 has a forwardly directed tapered point 52 which is formed oppositely to the point 39 of the construction illustrated in Figure 4.

The blade used with this master element is designated 53 and the thickened forward end part 54 of the point 55 has formed in the back part thereof the horizontal notch 56 which is tapered or pointed to receive the tapered point or tapered edge 52 of the landside bar.

The means employed for securing the blade 53 to the body of the master element 50 may be of any suitable character such as is commonly employed for securing a share to a landside and with this interlocking connection between the landside bar and the thickened point portion 54 of the blade it will be seen that a rigid or solid coupling between the parts is effected which will effectively resist bending strains which may be applied to the point in the various uses of the plow.

As is clearly shown in Figures 1 and 10 the landside is in part formed integral with the master element where the narrow double edge blade is employed. In the use of the full size blade or share as shown in Figures 6 and 7 the master element is not, of course, employed. In this event it becomes necessary and desirable to use a long landside as indicated at 57 in Figure 12. Such a landside would have a long forward end portion or point 58 which extends forwardly under the point 45 of the share 43 as illustrated thus providing the support for the point 45 which is provided by the landside element 51 of the master element for the point of the narrow blade 53.

From the foregoing it will be readily apparent that there is provided in the present invention an improved plow share construction in which the blade is designed in a novel manner whereby there may be obtained from the blade unit twice

as much service as is obtainable from share blades constructed in accordance with the present practice since each share or blade has two usable points and two cutting edges, one of which may be put into use after the other has served its purpose.

I claim:

In a plow share structure, a moldboard having a straight unbroken bottom edge extending the full length thereof, a bar depending from the forward end of the said bottom edge in continuation with the leading edge of the moldboard, a flat elongate share body having a straight intermediate portion of a length as great as the length of said moldboard edge and its longitudinal edges parallel and beveled to form cutting edges, oppositely and outwardly directed obliquely extending points formed at the ends of the share body, each of said points having a straight landside face which aligns with the landside face of the moldboard when the same is mounted in working position, each of said points being laterally and upwardly thickened a distance approximately one half of the width of the adjacent face of the share body to provide a shoulder at the upper end of the thickened portion against which the lower end of said bar abuts when the share body is in place, and means for securing the share body to the plow moldboard with a cutting edge in opposing relation to the said moldboard bottom edge, said share body when so secured having the rearwardly directed point thereof extending beyond the rear edge of the moldboard.
